UNITED STATES PATENT OFFICE.

EDWIN E. THOMAS, OF ST. PAUL, MINNESOTA, ASSIGNOR OF ONE-HALF TO UNION IRON WORKS, OF MINNEAPOLIS, MINNESOTA, A CORPORATION OF MINNESOTA.

GUIDE-OPERATING MEANS FOR BAND-SAW MILLS.

SPECIFICATION forming part of Letters Patent No. 694,697, dated March 4, 1902.

Application filed November 11, 1901. Serial No. 81,803. (No model.)

To all whom it may concern:

Be it known that I, EDWIN E. THOMAS, of St. Paul, Ramsey county, Minnesota, have invented certain new and useful Improvements 5 in Guide-Operating Means for Band-Saw Mills, of which the following is a specification.

In the operation of band-saw mills it is necessary to raise and lower the upper saw-guide 10 to adjust it according to the diameter of the log that is being sawed. The mechanism heretofore employed for this purpose is clumsy and slow of operation and is located where it interferes more or less with the other mechanism of the mill.

The object, therefore, of my invention is to provide a conveniently-operated means for effecting a quick accurate movement of the saw-guide.

20 A further object is to arrange the guide raising and lowering means where it will not be in the way of the operator or any of the operating mechanism and will not accumulate sawdust and other refuse material from 25 the saw.

The invention consists generally in providing a band-saw mill with a steam-cylinder located on the opposite side of the upper band-wheel shaft from the saw-guide, the piston of 30 said cylinder having oscillating connections with the saw-guide.

Further, the invention consists in various constructions and combinations, all as hereininafter described, and particularly pointed 35 out in the claims.

In the accompanying drawings, forming part of this specification, Figure 1 is a plan view of a band-mill embodying my invention. Fig. 2 is a rear view of the same.

40 In the drawings, 2 represents the band-mill base, provided with upright brackets 3, having vertical bearings for the sliding columns 4, whereon the shaft 5 of the upper band-wheel 6 is supported.

45 7 represents the lower band-wheel, and 8 its shaft suspended in adjustable bearings 9 on the mill-base.

50 10 represents a substantially V-shaped bracket provided on one of the brackets 3 and has a vertical bearing-surface 11, where-

on a casting 12 is slidable. The casting 12 is provided with sleeves 14, preferably integral therewith, to receive the ends of shafts 15, whereon the freely-swinging guide-arms 16 are hung between adjustable clamp-collars 17. 55

One of the swinging arms 16 is provided with a counterbalance-weight 18 and with a bearing 19 for an antifriction-wheel 20. In case the guide is set too low on the saw for the diameter of the log that is to be sawed, 60 the end of the log will strike the antifriction-wheel below its center and raise the guide. Without the employment of this wheel the log would strike the end of the guide and break the same or jam it against the saw or 65 otherwise cause damage to the band-mill and interfere with its operation.

21 represents the guide proper, having jaws 22, provided with a space between them to raise the saw. It frequently happens in sawing that the guide has to be raised or lowered to accommodate it to logs of different diameter. As large logs may be mixed with the small ones, the operator is obliged to raise and lower the guide a number of times daily 75 during the operation of the mill. To enable the operator to handle the guide quickly and easily, I provide a sway-bar 22, pivoted on a short stud 23 near the top of one of the brackets 3, one end of said bar being connected by a rod 24 with the casting 12. The other end of the bar overhangs the base of the mill on the opposite side of the upper band-wheel shaft from the saw-guide, and on the base at this point I arrange a steam-cylinder 26, having its piston 25 connected with the overhanging end of said sway-bar. I consider the arrangement of a cylinder in this position as the important feature of my invention, as it removes the cylinder from all 80 danger of interference with the other mechanism of the mill and locates it where it will be free from the sawdust and other refuse that accumulate around the saw. The cylinder is provided with a slide-valve 27, having inlet and exhaust pipes 28 and 29. The valve 27 is so arranged that when it is in its normal position steam will be admitted to each side of the piston and the piston will be locked 85 against movement in either direction. The 100

valve 27 is so arranged that when it is in its normal position steam will be admitted to each side of the piston and the piston will be locked against movement in either direction. The 100

stem of the valve is connected by a rod 30 to an arm 31, secured on a shaft 32. An arm 33 is also secured on said shaft and connected by a rod 34 with an operating-lever 35, that 5 is pivoted on the base of the mill. The lower end of the lever 35 has a weight 36, which normally tends to hold said lever in a vertical position and allow the steam to enter through the valve 27 to both ends of the cylinder.

- 10 To operate the guide, the operator moves the lever and shuts off the steam from one side of the piston. The saw-guide will then be moved up and down, according to the direction the lever is moved. As soon as the 15 lever is released the weight will cause it to automatically assume a vertical position.

I claim as my invention—

1. In a band-mill, the combination, with a base having upright brackets, of the upper 20 band-wheel and its shaft supported on said brackets, a saw, a vertically-movable saw-guide, an engine arranged on the opposite side of the upper band-wheel shaft from said guide to remove it from the dust and dirt of 25 the saw and from interfering with the work of the operator, means for controlling said engine, and a lever pivoted on one of said brackets and having its ends connected respectively with said engine and with said 30 guide, substantially as described and for the purpose specified.

2. The combination, with a band-mill base provided with upright brackets, of the upper and lower band-wheels and the saw thereon, a vertically-sliding saw-guide, a steam-cylinder, a sway-bar connected respectively to said guide and the piston of said cylinder and pivoted at an intermediate point on one of said brackets, and a lever having operative connections with the cylinder-valve. 35

3. In a band-mill, the combination, with a sawmill-base provided with suitable brackets or supports, of the upper band-wheel and its shaft supported on said brackets, a vertically-movable saw-guide, a sway-bar pivoted at a 40 point intermediate to its ends on one of said brackets above said shaft and said guide, an engine provided on the side of said shaft and said brackets opposite said guide and the saw, whereby it is removed from the dust and dirt 45 of the saw and from interfering with the work of the operator, means pivotally connecting the ends of said sway-bar with said guide and engine, and an operating-lever for controlling said engine. 50

In witness whereof I have hereunto set my hand this 7th day of November, 1901.

EDWIN E. THOMAS.

In presence of—

RICHARD PAUL,
M. C. NOONAN.
